B.J. Noyes, Atty

UNITED STATES PATENT OFFICE.

LESTER E. THOMPSON, OF MEDFORD, MASSACHUSETTS.

TWYER.

1,293,985.

Specification of Letters Patent. Patented Feb. 11, 1919.

Application filed July 14, 1917. Serial No. 180,690.

To all whom it may concern:

Be it known that I, LESTER E. THOMPSON, a citizen of the United States, and a resident of Medford, county of Middlesex, and State of Massachusetts, have invented an Improvement in Twyers, of which the following is a specification.

My invention relates to boilers and has specific reference to such boilers equipped with mechanical coal feeding means and to which the air for combustion is applied under pressure.

Steam boilers of large capacity are customarily equipped with apparatus or stokers, whereby the coal used as fuel is introduced in the fire box under the boiler automatically and mechanically by the use of reciprocating plungers, which operate to force the coal from a hopper through conduits into the fire box, traveling belts which serve to carry the fuel under the boiler, or by other similar means.

The coal is introduced into the fire box, as heretofore stated, in channels or conduits, and between each coal channel there is disposed means for the introduction of air into the coal, whereby the coal may unite with said air and burn. The means commonly employed for the admittance of air into the coal consists of a series of flat plates or twyers, as they are commonly termed, superimposed in stepped rows one above the other between each of the coal channels. The twyers have suitable openings therethrough connecting with the air box, of which the rows of twyers form a wall, whereby air may flow from said air boxes into the mass of coal.

The twyers, as commonly constructed, are interlocking, and the top twyers of any series or row serves to lock all the lower twyers against displacement therefrom; and to remove any intermediate twyers in the series, it is necessary to remove in successive order the twyers located above the particular one, beginning with the top twyers.

When it is considered that these twyers are disposed in the hottest part of the fire box, where the temperature may run as high as 4,000 degrees Fahr., and when it is also considered that these twyers, for cheapness, are made of cast iron, it is seen that due to the action of the heat the individual twyers of the series can have but a short life and that it is necessary that constant replacements be made. The action of the intense

heat upon the cast iron located, as it is, in the reducing atmosphere of the fire box serves to burn the cast iron and make it extremely brittle and fragile. Inasmuch as the lower twyers of the series are subjected to the most intense heat, these twyers disintegrate more rapidly than the other twyers of the series, and it is therefore necessary to replace them more often.

In replacing the lower twyers of the series, it is necessary to disassemble the entire series, beginning with the top twyer and working successively downward. Due to the brittleness of the twyers it often happens that some of said twyers, which were in apparently good condition before the disassembling process become broken, and it becomes necessary to replace the broken twyers as well as the burnt twyers situated at the bottom of the row; so that in the replacement of the burnt out twyers, many more twyers of this series are broken, and it frequently happens that over half of the series have to be replaced because of the breaking of the twyers in their removal from the series.

In view of the above difficulties, it is an object of my invention to provide a twyer adapted for a position in a series of twyers, whereby said twyer may be extracted or removed from said series without the disturbance or removal of any other twyer of said series. I accomplish this result of my invention by the provision of means whereby each twyer may be independently pinned, or otherwise secured to the walls of the wind box or channel, and which pin or other securing means is adapted for ready removal independently of any other pin or securing means to admit of the consequent removal of any twyer of the series independent of any other twyer of said series.

In the customary form of twyer the locking means provided between any two twyers consists of a plurality of projections in one of said twyers adapted to fit in a corresponding plurality of indentations in the other of said twyers. When the said twyers are subjected to heat, the twyer consequently expands; and due to the unequal expansion of the two twyers, there results a tensional stress in both of said twyers, which resulted in the continual breaking of said twyers.

Another object of my invention is to provide means associated with the means securing said twyers to the channel of the wind box, whereby the stresses caused by

the expansion of the twyers due to heat do not operate to cause stresses in any part of the twyer which would tend to rupture the same.

- 5 Inasmuch as these twyers are interposed between the channels of coal, it is desirable that the greater quantity of air issuing through the ports of the twyers be directed in a sidewise direction into the mass of coal, 10 with but a small proportion of the total volume of air passing through said twyers being directed directly into the fire box; and consequently, another object of my invention is to provide means to accomplish this 15 result.

Figure 1 illustrates a side view partly in section of a fire box and a series of twyers constructed according to my invention.

- 20 Fig. 2 illustrates a partial front view of the fire box shown in Fig. 1.

Fig. 3 is a plan view of the twyer.

Fig. 4 is a bottom view of the twyer shown in Fig. 3.

- 25 Fig. 5 is a sectional detail of the air passage taken along lines 5—5 of Fig. 4.

Fig. 6 is a developed view of the air ports in the twyer.

Fig. 7 is a sectional detail showing relation of twyer and wind box.

- 30 As here shown, the twyer comprises a flat plate or block, having a pointed toe portion 10 and rearwardly extended ears 11, forming a heel portion through which a pivot pin or bolt 12 is adapted to be passed to secure said 35 twyer to the said walls 13 of the wind box. The twyer is formed of a width greater than that between the ears 11 and said side portions have beveled or tapered ends 14 adapted to conform with the taper of the walls of 40 the wind box 13, and to rest on the outer portion thereof to support the said twyer and maintain the same in a substantially horizontal plane. Between the rearwardly extended ears 11 the twyer is formed with an 45 inwardly extending recess 15, which serves as a conduit for the conduction of air to the passages in the twyer above and also to lighten said twyer. The toe portion 10 is formed with a series of teeth 16 the tops of 50 which rest on the top face of the next lower twyer in this series and the space between which teeth forms a conducting channel for the discharge of air into the coal from the air box. Said teeth are raised from the plate 55 structure as shown more clearly in Fig. 5, whereby the back of said twyer and the next lower one in the series form a conducting channel thereto, and the construction of which also serves to lighten said twyer.

- 60 The air passage of said twyer is constructed in a novel manner, in accordance with an object of my invention, whereby the greater part of the air issuing through the twyer into the fire box is directed to the sides of the 65 twyer and into the coal channels. Said teeth

are formed with a progressively decreasing pitch and depth from one side 17 to the flat toe portion 10 through the extent of which the pitch and depth of the teeth are maintained constant, from which the teeth increase in pitch and depth in a progressive manner to the other side portion 17. With this construction of tooth the maximum area of air passage formed thereby is located at the sides of the twyer, and consequently the greater part of the air discharged therethrough is directed into the greater mass of coal located at the sides thereof. 70 75

The twyers constructed as described are adapted to be placed in a series between the walls of the wind box, as shown more clearly in Fig. 1, and each twyer is independently pinned or secured to such walls. It is seen that with this construction, when the bottom twyer or any twyer of this series becomes so burnt or broken that replacement is necessary, the broken twyer may be removed from the series by the simple removal of its securing pin or bolt 12 without disturbing in any degree any other twyer in the series, 80 85 whereby the removal of any twyer does not cause the breaking of several other twyers, as has been heretofore the case. 90

It is also seen that, with the twyer secured against displacement at but one point, the forces set up in said twyer due to the heat can in no way operate to injure the twyer. 95

I claim:

1. In combination with the wind box of a boiler, of a series of superimposed twyers therein and means for independently locking said twyers to the wall of the wind box. 100

2. In combination with the wind box of a boiler, of a series of superimposed twyers therein and means for maintaining each of said twyers in position in said series independently of any other of said twyers. 105

3. In combination with the wind box of a boiler, of a series of superimposed twyers therein and means securing said twyers in position in the series adapted to permit the removal of any twyer independent of any other twyer in said series. 110

4. In combination with the wind box of a boiler, a series of superimposed twyers therein and independent means securing each twyer of the series in position in said series admitting of the independent removal of any twyer in said series. 115

5. In combination with the wind box of a boiler, of a series of superimposed twyers therein and means extending through said twyers and walls of said wind box to independently secure each twyer in place in said wind box. 120

6. In combination with the wind box of a boiler, a series of superimposed twyers therein, of a pin extending through each of said twyers and the walls of said wind box whereby each twyer is secured in place 125 130

- therein and whereby each twyer may be removed from said series independently of any other twyer of said series.
7. In combination with the wind box of a boiler having sloping side walls, of a twyer therefor adapted to be one of a series of superimposed tuyers in said wind box, and a pin detachably securing said twyer in said wind box against displacement therefrom, a component part of said twyer having a tapered portion adapted to engage a sloping side wall of said wind box to maintain said twyer in a substantially horizontal plane therewith, said pin and sloping portion of the twyer providing means for securing the twyer in the wind box independent of any of the tuyers of the series.
8. A twyer adapted to comprise one of a series of superimposed tuyers in the wind box of a boiler having a toe portion and a heel portion, said toe portion having air passages in the face thereof and said heel portion providing means whereby the twyer may be detachably secured in position in the wind box of a boiler independently of any other of the tuyers comprising said series.
9. A twyer adapted to comprise one of a series of superimposed tuyers in the wind box of a boiler having a toe portion, a heel portion and beveled side portions, said toe portion having air passages in the face thereof, said heel portion providing means whereby the twyer may be detachably secured in position in the wind box of a boiler independently of any other of the tuyers of said series and said beveled side portions providing means whereby said twyer may maintain a predetermined position with respect to the sloping side walls of the wind box.
10. A twyer adapted to be placed in a series of superimposed tuyers in the wind box of a boiler, and means arranged to secure said tuyers therein permitting a movement thereof independently of any other of the tuyers in the series.

11. A twyer adapted to be placed in a series of superimposed tuyers in the wind box of a boiler, and means arranged to secure said twyer therein permitting an expansion or contraction thereof unrestricted by any other of the tuyers of the series.
12. In combination with the wind box of a boiler of a series of superimposed contiguous tuyers, and means independently securing said tuyers in position permitting the independent expansion of said tuyers.
13. In combination with the wind box of a boiler, of a series of superimposed contiguous tuyers and means independently securing said tuyers in position permitting the unrestrained expansion of said tuyers.
14. In combination with the wind box of a boiler, of a series of superimposed contiguous tuyers, and means independently securing said tuyers in position permitting the independent and unrestrained expansion of said tuyers.
15. A twyer adapted for use in a series of superimposed tuyers in the wind box of a boiler having means whereby it may be secured in position in said series independent of any other twyer of the series.
16. A twyer adapted for use in a series of superimposed tuyers in the wind box of a boiler and means permitting the removal of said twyer from said series independently of any other twyer of said series.
17. A twyer adapted for use in a series of superimposed tuyers in the wind box of a boiler and means securing said twyer therein independently of any other twyer in the series and permitting the removal of said twyer therefrom independently of any other twyer of the series.

In testimony whereof I have signed my name to this specification in the presence of two subscribing witnesses.

LESTER E. THOMPSON.
